[57] CLAIM

The ornamental design for an electrically monitored coupling device, as shown and described.

DESCRIPTION

FIG. 1 is a perspective view of the present invention embodying our new design;

FIG. 2 is a front plan view;

FIG. 3 is a rear plan view;

FIG. 4 is a top plan view;

FIG. 5 is a side plan view, the opposite side plan view being a mirror image; and,

FIG. 6 is a bottom plan view.

FIG. 1

FIG. 3

FIG. 2

FIG. 4

FIG. 5

FIG. 6
